UNITED STATES PATENT OFFICE.

JOSEPH KRAMER, OF CHICAGO, ILLINOIS.

DESIGN FOR A POST-CARD.

No. 38,967.

Specification for Design.

Patented Dec. 31, 1907.

Application filed October 25, 1907. Serial No. 399,228. Term of patent 3½ years.

To all whom it may concern:

Be it known that I, JOSEPH KRAMER, a citizen of the United States, residing at Chicago, in the county of Cook and State of Illinois, have invented a new, original, and ornamental Design for Post-Cards, of which the following is a specification, reference being had to the accompanying drawing, forming part thereof.

The figure is a perspective view of a post card, showing my new design.

I claim:

The ornamental design for a post card, as shown.

JOSEPH KRAMER.
